UNITED STATES PATENT OFFICE.

ALBERT NICHOLSON, OF NEAL, KANSAS.

DEVICE FOR TOPPING KAFIR CORN.

1,125,379.

Specification of Letters Patent. Patented Jan. 19, 1915.

Application filed August 3, 1914. Serial No. 854,828.

To all whom it may concern:

Be it known that I, ALBERT NICHOLSON, a citizen of the United States, residing at Neal, in the county of Greenwood and State 5 of Kansas, have invented certain new and useful Improvements in Devices for Topping Kafir Corn; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of 15 this specification.

This invention relates to new and useful improvements in devices for topping Kafir corn and consists essentially in the provision of a simple and efficient device of this 20 nature so arranged that it may be applied to a wagon box in place of the usual end gate and affording means whereby one man may conveniently operate the same.

My invention comprises various details 25 of construction, combinations and arrangements of parts, which will be hereinafter fully described, shown in the accompanying drawings and then specifically defined in the appended claim.

30 I illustrate my invention in the accompanying drawings, in which:

Figure 1 is a rear elevation of my invention, and Fig. 2 is a top plan view.

Reference now being had to the details 35 of the drawings by letter, A designates a board or member, made preferably of the size of the end gate of a wagon, and which is adapted to take the place of the usual end gate when adjusted for use. Said board

40 A is provided with a circular-outlined opening B therein, and C designates a circular-outlined disk which is journaled in said opening and has fixed to one end thereof a shearing blade D which coöperates 45 with a horizontally disposed shearing blade

E which is fastened to the top of the board. A lever F is bolted or otherwise fastened to the rocking disk C, and a spring H is fastened at one end to a hook I upon the 50 short end of the lever and its other end is fastened to a hook K which is fastened to

the base of the board. A rod N is fastened at one end to the long arm of the lever and its other end is adapted to be bent at an angle to form a convenient means whereby 55 the foot of an operator may rest thereon when it is desired to tilt the lever for the purpose of causing the blades to shear.

The operation of my invention will be readily understood and is as follows:—The 60 spring will normally hold the plate D in the position shown in Fig. 1 of the drawings and, when it is desired to top the corn, the latter is laid over the stationary blade E and the operator, by pressing down upon 65 the rod N, may cause the blade D to shear against the blade E, thus cutting off the heads which would naturally drop into the wagon box to which the board is applied. After pressure of the foot is relieved from 70 the rod N, the parts will assume their formal positions.

By the provision of a device embodying the features of my invention, a simple and efficient mechanism is afforded whereby the 75 device may be operated by one man who may conveniently handle the corn and operate the device with his foot.

What I claim to be new is:

A device for topping Kafir corn, etc., 80 comprising, in combination with a supporting member provided with a circular-outlined opening therein, a circular disk mounted to rotate within said opening and one end of the same projecting beyond the inner 85 face of said member and its outer face flush with the opposite face of the member, a lever fastened to the outer face of the disk and serving to hold the disk from movement in one direction, a shearing plate 90 secured to the upper edge of the member and projecting beyond the inner face of the latter, and a shearing blade fastened to the inner face of the disk and adapted to shear against the inwardly projecting edge of 95 said plate.

In testimony whereof I hereunto affix my signature in presence of two witnesses.

ALBERT NICHOLSON.

Witnesses:

JOHN GRAFFON,

J. H. GRAFF.
